HANDLED CARTON

Joseph A. McElwee, Rittman, Ohio, assignor to
 The Ohio Boxboard Company, Rittman, Ohio,
 a corporation of Ohio

Application April 11, 1951, Serial No. 220,417

2 Claims. (Cl. 229—16)

1

This invention relates to handled paperboard cartons, and it has special reference to a carton primarily adapted for the packaging of bottled goods such as beer and other beverages in easily transportable multiples, the specially formed, integral handle member serving as a ready means whereby the completed package may be carried.

The carton of the invention has, in addition, structural characteristics whereby it is well adapted to the automatic packaging of groups or multiples of bottled goods and the like, particularly as disclosed in the copending application of Robert J. Hickin for patent for Packaging Method and Means, filed January 15, 1951, Serial No. 206,099, now Patent No. 2,616,289.

The primary object of the invention is to provide in a carton blank of a structure which is, in effect, capable of automatic set-up to carton form by line packaging machinery, parts which may be folded together to provide a relatively rigid, integral carrying handle preferably substantially coextensive with one top edge of the finished carton, thus leaving the area of the carton top free of obstruction so that a reclosable opening may be formed therein for inspection, removal and replacement of the contents.

Another object is to provide a carton which lends itself readily to the packaging and by-carton transportation of predetermined multiples of bottled goods, such as beer, and which, after opening and removal of the contents may serve as a carrier for the return of the empty bottles.

The invention comprises, broadly, a carton having a bottom wall, side walls extending from said bottom wall and having laterally extending flaps preferably joined to the bottom wall by gusset-folding members and adapted to have their free edges joined in a seam to provide the end walls, and flaps extending from the free edges of the side wall members and relatively foldable and interfoldable to provide a top wall and an off-standing handle member, the handle member preferably being located at one side wall edge of the formed top wall, and the top wall preferably being provided with frangible opening-forming means in the nature of a reclosable panel or flap, all as will be explained hereinafter more fully and finally claimed.

In the accompanying drawings illustrating the invention, in the several figures of which like parts are similarly designated,

Fig. 1 is a plan view of the inner face of the paperboard blank for forming the carton of the invention,

Fig. 2 is a view similar to Fig. 1 but showing the

2

end wall forming flaps and gusset-folding members folded flat against adjacent parts of the blank, the glue areas also being indicated,

Fig. 3 shows, in perspective, a step in the progressive erection of the blank to set-up carton form,

Fig. 4 is a top view of the erected carton blank before the closing and assembling of the top wall and handle-forming members,

10 Figs. 5, 6 and 7 are top views progressively illustrating the assembling and folding of the top wall and handle forming members,

Fig. 8 is a view similar to Fig. 7, but showing the access panel or flap partially torn from the top wall along its prepared lines of rupture and folded back,

15 Figs. 9, 10 and 11 are enlarged fragmentary side elevations showing the top wall and handle forming members in arrangement corresponding to the showing of Figs. 5, 6 and 7, respectively,

Fig. 12 is an enlarged fragmentary sectional view substantially medially of the side wall members, top and handle member as shown in Figs. 7 and 11,

20 Figs. 13 and 14 are enlarged fragmentary perspective views, taken from opposite sides of the carton, showing, in greater detail, the formation of the top wall and handle member,

Fig. 15 is a side view of the finished filled carton, the contained bottles and cellular separator strip means being shown in broken lines, and

25 Fig. 16 is an end view of the package shown in Fig. 15.

Having reference particularly to Fig. 1, it will be seen that the blank from which the carton 30 of the invention is formed comprises an integral sheet of appropriate paperboard material provided with suitable folding scores and cuts defining a bottom wall member 1, side wall members 2 and 3 and end wall forming members 4, 4' and 5, 5' formed as lateral extensions of flaps on the side wall members 2 and 3, respectively, and joined to the bottom member 1 and to each other by gusset-folding members 6, 6'. One of the side wall members (2) is provided at its free outer edge 35 with a top forming flap member 7 having lines of cut-scores or perforations 8, 8, 8 joining a folding score 9 defining the top edge of the side wall member 2 and providing a rupturable panel or flap 10 to form an access opening to the interior of the finished carton, as will be explained hereinafter, and from the outer edge of this top forming flap 7, defined by a folding score 11, extends a handle-forming member 12 provided with appropriate finger openings 13.

From the outer free edge of the other side wall member 3, defined by a folding score 14, extends a pair of handle-forming members 15, 16, complementary to each other and to the previously described handle-forming member 12, and relatively foldable upon an intermediate substantially medial folding score 17. These handle-forming flaps 15 and 16 are provided, respectively, with finger openings 18, 19 complementary to those, 13, of the first named handle-forming flap 12, and the cuts which form the finger openings 19 of the outermost flap 16 extend on three sides only of the openings to provide protection and bearing tabs 20 foldable upon score lines 21 as will later be described.

The free outer edges of the end wall members 4, 4' and 5, 5' are provided with closure flaps 22, 22' and 23, 23', respectively, separated from laterally spaced adjacent portions of the blank by appropriate cuts and are foldable relatively to the end wall members upon extensions of the folding scores 9 and 14, respectively.

In setting up the blank to carton form, the end wall members 4, 4' and 5, 5' with their gusset-folding members 6, 6' and closure flaps 22, 22' and 23, 23', are folded inwardly and flat against the side and bottom wall members 2, 3 and 1, upon the longitudinal folding scores 24, 24'; 25, 25' and 26, 26', as shown in Fig. 2. Then the side wall members are bent upwardly, as shown in Fig. 3, upon the bottom folding scores 27, 27', and this manipulation will cause the gusset-folding members 6, 6' to fold upon their diagonal folding scores 28, 28' and parallel folding scores 29, 29', thus raising the end wall members 4, 4' and 5, 5' to erected, overlapping relation 30, Fig. 4, where they are secured at appropriate areas *a*, Figs. 2 and 3, to square up the carton body. Next, the closure flaps 22, 22' and 23, 23' are folded inwardly upon their folding score extensions 9 and 14, Figs. 5 and 9, and then the top-forming flap member 7 is folded down upon them upon its folding score 9 with its handle-forming member 12 folded upwardly upon its folding score 11 to lie in face-to-face contact with the handle forming member 15 of the side wall member 3, as shown in Figs. 6 and 10, and thereafter the handle-forming member 16, which now extends upwardly above those 12, 15 thus assembled is folded downwardly upon the intermediate folding score 17 into face-to-face contact with the outer face of the handle member 12 of the top-forming flap 7, Figs. 7 and 11 to 14, and its bearing tabs 20 may then, or later when the carton is handled by a purchaser of the package, be bent outwardly upon their score lines 21 to pass through the finger openings 13 and 18 of the other handle members.

It will be understood that, as the assembly of the top-closing and handle-forming parts progresses, these parts will be successively secured in set-up condition upon appropriate glue areas *b*, *c* and *d*, Figs. 2 and 3.

The handle member thus formed being of three ply construction and connected with two walls, side and top, of the carton, is not only relatively rigid, and of itself fracture resistant, but tends to resist the strain of handling of the carton by distribution of such strain over the two adjacent walls, thus guarding against its tearing away from the carton. Moreover, by the arrangement of the handle member at an edge of the carton the area of the top wall is left free for the provision of an access opening as provided by the rupturable panel of flap 10.

Obviously, the commodity to be packaged, say bottled goods or the like *e*, with a cellular arrangement of partition strips *f*, Figs. 15 and 16, may be deposited in the carton after it has been set up to the condition shown in Fig. 4, and the top closure and handle-forming members thereafter assembled, as described, or where the carton is used in a line packaging operation, as disclosed, for example, in the copending application of Robert J. Hickin hereinbefore referred to, it may be foldingly assembled, preferably from the blank form shown in Fig. 2, around and enclosing predetermined groups or multiples of bottles or the like and separator strip assemblies appropriately associated with it in the packaging operation.

As hereinbefore indicated, access to the contents of the package provided by the carton, Figs. 15 and 16, may be had by tearing away the rupturable panel or flap 10 upon the cut-scores or perforations 8, Fig. 8, so that this flap will hinge upon the folding score 9 at the upper edge of the side wall 2, and if the carton is to be reused after the contents have been removed, as for return of the empty beer bottles or the like, the flap 10 may be used as a closure to again provide a presentable package.

Various changes and modifications are considered to be within the principle of the invention and the scope of the following claims.

What I claim is:

1. In a handled carton, a body comprising a bottom wall member, a top wall member, and two side wall members, each of said side wall members carrying at each of its side edges a part of an end wall member, said end wall parts being joined in pairs to each other and to the bottom wall member by a gusset-folding member, and each pair of same being edge joined to form a complete end wall, said top wall member being integral with and an extension of one of said side wall members and provided with a handle extension, and the other side wall member being provided with a handle extension, one of said extensions being substantially double the area of the other said extension, said handle extensions offstanding from the junction of said top wall member and said side wall member and being secured together with the extension of double area medially folded and arranged in face-to-face contact with both faces of the other extension to form the carton handle in multiply arrangement and to fix the top wall member in carton closing condition.

2. A blank for a handled carton, comprising a sheet of paperboard material appropriately cut and scored to define a bottom member, a pair of similar side wall members, one of which is at an end of said blank, end wall members connected with said side wall members, said side and end wall members being connected with said bottom member, a top closure member extending from the other of said side wall members and arranged at the other end of the blank and provided at its free edge with a handle-forming extension, and a handle-forming extension provided on the free edge of the first-named side wall member, one of said extensions being of substantially double the area of the other extension and adapted for cooperation with the said other extension by face-to-face folding thereover when the top closure member is in carton closing condition, thereby to locate the assembled handle member at the junc-

tion of said side wall member and top closure member.

JOSEPH A. McELWEE.
